CLAIM

The ornamental design for a tray for cosmetics and sundries, as shown and described.

DESCRIPTION

FIG. 1 is an exploded isometric view of a tray for cosmetics and sundries showing my new design;

FIG. 2 is an isometric view in assembled condition;

FIG. 3 is a top plan view on an enlarged scale;

FIG. 4 is a front elevational view on an enlarged scale;

FIG. 5 is a bottom plan view, on a smaller enlarged scale;

FIG. 6 is a rear elevational view thereof;

FIG. 7 is a left side elevational view, the right side being a mirror image;

FIG.3
